UNITED STATES PATENT OFFICE.

GEORGE CROSSLAND, OF WATERTOWN, MASSACHUSETTS, ASSIGNOR TO GEORGE H. BRIGGS, OF AMESBURY, MASSACHUSETTS.

CUTTING PILE-WIRE.

978,116.

Specification of Letters Patent.

Patented Dec. 6, 1910.

Application filed June 28, 1909. Serial No. 504,445.

To all whom it may concern:

Be it known that I, GEORGE CROSSLAND, a citizen of the United States, residing at Watertown, in the county of Middlesex and

5 State of Massachusetts, have invented certain new and useful Improvements in Cutting Pile-Wires, of which the following is a specification, reference being had therein to the accompanying drawing.

10 This invention relates to the construction of stationary pile wires having pile thread cutters mounted thereon, the same being used on looms employing longitudinal pile wires for weaving pile fabric, and the object of the invention is to provide a pile wire having a reduced portion for the purpose of relieving the friction in drawing the loops along said wires after having been formed thereover.

15 20 A further object of the invention is to provide a reciprocating cutter mounted upon said wire for severing the pile loops of the fabric.

A feature of my invention is that the 25 cutter blade is arranged to reciprocate, thereby giving it many advantages over the ordinary stationary blade, among others being, first, that the moving blade cuts much easier than a fixed blade; second, that owing to 30 this ease in cutting, the pile loops are severed exactly in the center; third, my construction gives to the blade a greatly increased length and more effective cutting edge; fourth, by my improved construction 35 the cutter is very easily removed to be inspected, sharpened or replaced.

With these and other objects in view, the invention consists of certain novel features of construction, as will be more fully described and particularly pointed out in the appended claims.

In the accompanying drawings: Figure 1— is a side elevation of the device illustrating the cutter in position and showing a 45 connection through which the same may receive a reciprocating motion. Fig. 2— is a plan view of the apparatus. Fig. 3— is a detail view of the pile wire showing the cutter operatively mounted thereon. Fig. 4— is 50 an enlarged detailed view of the cutter.

Referring to the drawings, 1 designates the pile wires, one end of each of which is provided with a shoe 2 or enlarged portion on its forward end. This enlarged end may 55 be formed integral with the wire or attached

to the same by rivets, solder or other suitable means. This end of this shoe is provided with an upward extension 3 to facilitate its being clamped or retained in position. This end is also provided with a 60 forked rearward extension 4 for the reception of the cutter blade 5 which is mounted to oscillate therein on the pivot pin 6. The lower portion or cutting edge of this blade works in a slot 7 in the upper edge of the 65 pile wire, the upper end 8 of the blade being rounded off on a radius struck from the pivot center, so that the cap or driving bar 9, which rides thereon, will move back and forth in a straight line while reciprocating. 70 Another feature in the construction of this blade is that the same is provided with an open-ended slot 10 extending forward and downwardly from the pivot bearing, the walls of which slot form a hook which is 75 adapted to fit over the pivot pin 6 when positioning the cutter thereon. This slot is for the purpose of allowing this cutter blade to be readily removed from the pivot pin 80 when desired without the necessity of removing said pin.

Pile wires provided with cutter blades are usually formed of a uniform size from the point 11, where the loop is first formed thereover, forward to the edge of the knife, 85 where the loops are cut, thus requiring a large amount of power to overcome the friction of sliding the multiplicity of loops along the wires. In order to remove this unnecessary friction and reduce the power 90 required for this purpose I form the pile wire of the usual size at the point 11 and maintain this size a short distance or until sufficient ground-work has been woven into the fabric to firmly bind and retain the 95 pile threads, after which the size of the wire is reduced as at 12 for a short distance, sufficiently to allow the loops to pass freely and without friction over this portion of the wire. Just before the loops reach the 100 edge of the knife the wire is again enlarged as at 13, substantially to its normal size, to tighten or stretch the loops so they may be readily severed when presented to the knife. The rear end of these pile wires may be free 105 and unsupported, if desired, and arranged to extend back through the reed. In order to firmly support these wires from their front ends I have provided a frame 14 having a cross bar 15 which extends across the 110

- front of the machine, against which bar the shoes or forward ends 2 of the pile wire are arranged to rest, the lower edge 16 of the shoe resting on the ledge or outwardly 5 extending lip 17 of this bar, while the clamping plate 18 is bolted across the front engaging the up-turned end 3 of each wire, firmly binding and holding the whole firmly in position.
- 10 The cap or driving bar 9 is arranged to rest upon the upper rounded ends of the cutter blades and is allowed to reciprocate, but is prevented from rising by the arms 19 which are bolted at 20 to the bar 15, the required reciprocating motion being imparted 15 from a cam or crank on the loom, (not shown,) through the connecting rod 21, knee lever 22, rack 23, pinion 24, lever 25 and connecting rod 26. This cap bar 9 may be made to engage all of the cutters or it 20 may be in sections to engage any number of the cutters desired, the means for imparting the reciprocating motion being connected to each end of each section. When it is 25 desired to remove a cutter it is only necessary to loosen the bolts 20, swing away the fingers 19, raise the bar 9 and withdraw any or all of the cutters, the same being as readily replaced therein.
- 30 It is found in practice that a reciprocating cutter is extremely effective in its operation as it is well known that a moving or shearing blade will cut much more effectively than a fixed blade, also that the cutter will hold its edge much longer owing to the fact 35 that a much greater length of effective cutting edge is being presented. Then again, the moving cutter will cut the loops exactly in the center, while with a fixed blade they 40 are apt to run from side to side over this edge, cutting one thread longer than the other. Another essential feature is the ease with which the cutters may be removed for the purpose of inspecting, sharpening or 45 replacing the same.
- Having thus described my invention, what I claim as new and desire to secure by Letters Patent, is:
1. In a loom the combination of a continuous pile wire provided with a slot near one end thereof and provided with an upward extension adjacent said slot, a reciprocating cutter blade pivotally supported by said extension and having its cutting edge located in said slot, and means for reciprocating said blade to sever the pile loops as drawn along said wire.
  2. In a loom the combination of a continuous pile wire provided with a slot near one end thereof and provided with a shoe or enlarged portion having a rearward extension overhanging said slot, a reciprocating cutter blade pivotally supported by said extension and having its cutting edge located in said slot, and means for reciprocating

cating said blade to sever the pile loops as drawn along said wire.

3. In a loom the combination with a pile wire, of a pivot rod, a pile cutting knife directly mounted on said pivot rod and removably engaging the latter, and means for operating said knife.

4. In a device of the character described, the combination of a pile wire, a reciprocatable cutter blade pivotally hung, said blade being provided with a slot whereby it may be readily removed from its pivot, and means for reciprocating said blade to sever the pile loops as drawn along said wire.

5. In a device of the character described, the combination of a pile wire, a reciprocatable cutter blade pivotally hung, said blade being provided with an open-ended slot from its pivoting point to its edge whereby it may be readily removed from its pivot, and means for reciprocating said blade to sever the pile loops as drawn along said wire.

6. In a device of the character described, the combination of a pile wire provided with an enlarged portion at one end, a pivot pin in said portion, a cutter blade mounted on said pin, said blade being provided with an open-ended slot from its pivoting point to its edge whereby it may be readily removed from said pivot pin, and means for reciprocating said blade to sever the pile loops as drawn along said wire.

7. In a loom, the combination with a plurality of pile wires, of a pivot rod, a series of pile cutting blades directly mounted on said pivot rod, and removably engaging the latter, a member for retaining said blades in position, and means for reciprocating said member to operate said blades.

8. In a loom, the combination with a plurality of pile wires, of a pivot rod, a series of pile cutting blades directly mounted on said pivot rod, and removably engaging the latter, said blades being each provided with a cutting edge and an operating head, a removable cap engaging said heads, and means for reciprocating said cap to operate said blades.

9. As an article of manufacture, a continuous pile wire supported at the breast beam and having its upper edge provided with a reduced portion forward of that portion over which the loops are formed, said reduced portion being for the purpose of relieving the friction of drawing the formed loops along the pile wire, and also for retaining and guiding the same by the cutter, said wire being again enlarged nearer its cutting end and a cutter supported by said wire for severing the pile loops.

10. In a loom the combination with a plurality of pile wires, of a series of independent pivotally mounted cutting members each

provided with an operating head, a cap fitting over the heads of all of said cutting members, and means for reciprocating said cap.

5 11. In a loom the combination with a plurality of pile wires, of a series of independent pivotally mounted cutting members each provided with an operating head, a cap loosely engaging the heads of said cutting

members, means for reciprocating said cap, 10 and guide arms for retaining said cap in operative position.

In testimony whereof I affix my signature in presence of two witnesses.

GEORGE CROSSLAND.
